UNITED STATES PATENT OFFICE

GEORGE D. WYANT, OF ALLISON, PENNSYLVANIA, ASSIGNOR OF ONE-HALF TO
D. D. DODGE, OF UNIONTOWN, PENNSYLVANIA

HAND PROTECTOR

Application filed October 15, 1932. Serial No. 637,863.

The invention relates to hand protectors, and more particularly to shields for protecting hands from injury by tools and the like.

In operations requiring an object to be held or steadied by a workman's hand while the object is worked upon by a tool, it sometimes happens that the tool accidentally strikes the holding hand, causing injury thereto. For example, in the cutting of points or wedge ends on posts, stakes and the like, such as may be used in shoring up the walls of mine shafts, the workman generally grasps a stake with one hand while he chops the stake with an ax swung by the other. It often happens that the stake is held in such a way as to expose the holding hand to the blade of the ax which occasionally, especially when being swung in cramped quarters, is accidentally deflected from its intended path and caused to strike that hand. This is nearly certain to result in severe injury to the hand, and is likely to cause the loss of one or more fingers.

It is among the objects of this invention to provide a hand shield which protects a hand from accidental blows of tools, is held in place without substantially restraining free use of the hand, can be worn on either hand interchangeably, can be quickly and easily put in place or removed, is not uncomfortable to wear, and which is simple in form and inexpensive to manufacture.

The preferred embodiment of the invention is illustrated in the accompanying drawing, of which Fig. 1 is a bottom plan view of a shield, showing it in place on a hand; Fig. 2 a side view of the shield viewed from the top of Fig. 1; and Fig. 3 an end view thereof.

Referring to the drawing, a hand protecting shield 1 is preferably made from rigid blow-resisting material, by which is meant a material, such as metal, composition or the like, which is capable of withstanding the blow of an ax or hammer, etc. As the shield is adapted to be worn on the hand, it is also desirable that the material of which it is constructed be not only blow-resisting, but light in weight so as to not unduly tire or hamper the hand, aluminum being well suited to this purpose. If the shield be

made from metal, it may readily be formed by bending a substantially rectangular blank to the shape preferred according to this invention.

The shield is arched transversely (Fig. 3) to enable it to overlie the sides of the hand as well as the back thereof, thereby giving protection to all parts of the hand except the palm, which engages and is protected by the object being held. The corner portions 2 of the inner or thumb side of the shield are preferably turned down to further protect the inner side of the hand and to render the shield less cumbersome.

To permit the shield to be held in protecting position over the hand of a workman, and, what is an important feature of this invention, to allow at the same time substantially unrestrained freedom of movement of the hand, the shield is provided under the lower face of its inner side with a loop 3 adapted to slip over the thumb. Although this loop may be formed from a separate member connected to the shield, it is preferable to form it from an integral tongue portion cut transversely from the inner side of the shield and looped back and under. The edges of the tongue are smoothed and curved outward slightly to prevent them from cutting into the thumb.

It is desirable that the shielded hand be left substantially free to function, for, otherwise, if it were hampered by the shield, workmen would be unwilling to take advantage of the protection afforded by the shield. Furthermore, in some cases the interference of a shield with the hand might render its use impracticable or even impossible.

As some people are left-handed, or, due to the surroundings, may find it necessary to hold an object with the right hand, it is desirable that the shield be adapted for use with either hand at will. For this reason the loop-forming tongue is cut from the shield substantially midway of its length the portions of the shield at each side of the loop 3 being symmetrical in order that the shield may protect either hand equally well.

The edges 4 at the ends of the shield are

turned obliquely outward to prevent them from cutting into the wrists. It is also desirable that each end of the shield be provided with a hole 5 through which suitable means may be passed for locking the shield with other tools after work, as is the practice especially where workmen labor in shifts with their own tools. The inside face of the shield may be padded with a suitable cushioning material 6, such as felt or rubber, to make it more comfortable to wear and to prevent the back of the hand from being skinned or otherwise injured in case an ax or other tool strikes the shield.

15 The shield being held on the back of either hand by merely slipping a thumb through the loop, as shown in Fig. 1, and there being no straps and buckles nor other fastening devices necessary for holding it 20 in place, it is, therefore, adapted to quick and easy application and removal. The method of attachment provided by this invention also permits the shielded hand to be used practically as freely as normally, 25 even the thumb not being completely restrained. As set forth above, this is a material advantage.

The shield being interchangeable as to hands, both left and right hand shields need 30 not be provided, thereby making it unnecessary for a workman to be equipped with two shields. All parts of a hand which would otherwise be exposed are adequately covered and protected, but, nevertheless, the 35 shield is very simple in form. Likewise, being made preferably in one piece, it is inexpensive and easy to manufacture.

According to the provisions of the patent statutes, I have explained the principle and 40 mode of operation of my invention, and have illustrated and described what I now consider to represent its best embodiment. However, I desire to have it understood that within the scope of the appended claims, the 45 invention may be practiced otherwise than as specifically illustrated and described.

I claim:

1. A hand-protector for shielding a hand from blows of a tool, comprising a shield of 50 blow-resisting material, and means associated therewith adapted to be engaged by a thumb and forming the sole means for holding said shield in protecting position over the back of a hand, said means being disposed on the same side of the shield as said hand.

2. A hand-protector for shielding a hand from blows of a tool, comprising a rigid

shield of blow-resisting material, and means integral therewith adapted to be engaged by either thumb for holding said shield in protecting position over the back of either hand while permitting substantially unrestrained use of said hand, said means being disposed on the same side of the shield as said hand and forming the sole means for holding said shield in protecting position over the back of the hand.

3. A hand-protector for shielding a hand from blows of a tool, comprising a substantially rigid shield of blow-resisting material and a loop portion connected thereto and adapted to be engaged by a thumb for holding said shield in protecting position over the back of a hand, said loop portion being disposed on the same side of the shield as said hand and forming the sole means for holding said shield in protecting position over the back of the hand.

4. A hand-protector for shielding a hand from blows of a tool, comprising a substantially rigid shield of blow-resisting material, and an underlying loop portion integral therewith substantially midway of its length and adapted to be engaged by either thumb for holding said shield in protecting position over the back of either hand.

5. A hand-protector for shielding a hand from blows of a tool, comprising a substantially rigid shield of blow-resisting material, and a tongue cut from said shield substantially midway of one side thereof and looped back and under to provide a loop adapted to be engaged by either thumb for holding said shield in protecting position over the back of either hand, the corner portions of the tongue side of said shield being turned down.

6. A hand-protector for shielding a hand from blows of a tool, comprising a shield formed from a substantially rectangular blank of metal arched transversely of the hand and having the corner portions of one side turned down, a tongue cut from said shield substantially midway of said downturned corners and looped back and under to provide a loop adapted to be engaged by a thumb for holding said shield in protecting position over the back of a hand, and cushioning means connected to the inner face of said shield for contact with the hand, the ends of the shield being curved upward to prevent the edges of the ends from cutting into the wrists.

GEORGE D. WYANT.
